United States Patent Office

Des. 194,640
Patented Feb. 19, 1963

194,640

MOTION PICTURE CAMERA OR SIMILAR ARTICLE

Isamu Kubota, Hirakatashi, Osaka, and Shoh Shiramatsu,
Sumiyoshi-ku, Osaka, Japan, assignors to Chiyoda
Kogaku Seiko Kabushiki Kaisha, Osaka, Japan, a cor-
poration of Japan

Filed July 11, 1962, Ser. No. 70,874

Term of patent 14 years

(Cl. D61—1)

FIG. 1 is a side elevational view of a motion picture camera or similar article showing our new design.

FIG. 2 is a front elevational view thereof.

FIG. 3 is a plan view thereof.

FIG. 4 is an elevational view of the side opposite to that shown in FIG. 1.

FIG. 5 is a rear elevational view thereof.

FIG. 6 is a bottom view thereof.

We claim:

The ornamental design for a motion picture camera or similar article, as shown.
